UNITED STATES PATENT OFFICE.

CHARLES VERDAN, OF STRASBOURG, AND LOUIS MARIE JEAN LOISEAU, OF PARIS, FRANCE, ASSIGNEES TO COMPAGNIE FRANCAISE POUR L'EXPLOITATION DES PROCEDES THOMSON-HOUSTON, A FRENCH LIMITED COMPANY, AND ATELIERS J. CARPENTIER, A FRENCH LIMITED COMPANY.

SIGNALING SYSTEM APPLICABLE TO TELEGRAPHY AND TELEMECHANICAL TRANSMISSION.

Application filed May 25, 1925, Serial No. 32,782, and in France June 4, 1924.

In numerous signal transmission systems, such as telegraphy, for example, distinct disturbances of the signals transmitted by the sending station may make themselves felt at 5 the receiving station, resulting in reception of supplementary or erroneous signals which do not correspond to the signals sent. The message will then be unintelligible or difficult to decipher.

10 This is particularly the case where the communications are effected by wireless signaling and where the transmitting and receiving devices are connected to suitable antennæ; atmospheric influences, acting, for 15 example, on the receiving antenna, may cause wrong messages to be received.

Certain signal transmission systems are so devised that these parasitic disturbances can only occasion on reception additional 20 signals distinct from the signals desired.

The present invention has for its object a method and apparatus which permit the utilization of these transmission systems in such wise that the messages can be easily 25 deciphered on reception or transmitted without error to the receiver in spite of the action of numerous disturbing influences of foreign origin at the sending station.

As an example of a system in which such 30 parasitic influences can only occasion at the receiving end supplementary signals distinct from the desired signals, reference may be made to the Baudot telegraphic system. Transmission with this system may, as is 35 well known, be effected by wireless, the transmitting and receiving devices being associated with antennæ.

If in a system of the character above described there are repeated n times at the 40 transmitting end the signals desired to be transmitted at given intervals of time greater than the normal duration of a series of parasitic disturbances, there will be obtained at the receiving end n signals. If the 45 system and mode of transmission are such that it is known at the receiving end how to check the signals corresponding to the successive receptions of the same initial signal, it will suffice to select from among these 50 signals those which are identical; for an error to arise, it would be necessary that one of the "parasites" be produced at intervals

of time equal to those which separate the successive emissions belonging to the same signal and that they all produce on the receiver the same effects as the signal desired. 55

For example, the message may be repeated n times, at constant speeds $v_1, v_2 \dots v_n$ respectively there being taken in at the receiving station only the signals reproduced in all 60 the messages at the same relative instants.

Again, each signal may be repeated at intervals of time $t_1, t_2 \dots t_n$ greater than the normal duration of a series of "parasites", 65 there being taken in at the receiving station only the signals which are reproduced according to this rule.

The invention will be understood on reference to the following detailed description and to the accompanying drawings in which 70 Figs. 1 and 2 are diagrams showing the action of the "parasites" on a Baudot telegraphic station. Figs. 3 and 4 show diagrammatically how, according to the present invention, the "parasites" are prevented 75 from acting on a Baudot telegraphic station. Fig. 5 shows diagrammatically a telegraphic station on the Baudot system modified according to the present invention in such wise as to give the messages directly 80 without errors. Fig. 6 shows diagrammatically the transmission station corresponding to the receiving station of Fig. 5.

There will be described subsequently other embodiments of the invention applicable 85 particularly to apparatus for rapid automatic transmission, or employing perforated tapes.

If it be considered first how, in actual conditions, a telegraphic apparatus on the Baudot system, considering a single sector only, 90 would effect the transmission of the word "Paris" by wireless (see Fig. 1) there are obtained:

At the first rotation, emission on the 5 95 contacts of the distributor, letter P.

At the second rotation, emission on the 1st contact, letter A.

At the third rotation, emission on the 3rd, 4th, 5th contacts, letter R. 100

At the fourth rotation, emission on the 2nd, 3rd contacts, letter I.

At the fifth rotation, emission on the 3rd, 5th contacts, letter S.

If no parasitic signal appears at the receiving station during the transmission of the word "Paris," the registration will be correct, but, if, on the contrary, untimely 5 vibration of the receiving antenna takes place during the time under consideration, registration will be defective. In particular, if an atmospheric discharge or disturbance is produced according to the hatched 10 curve of Fig. 2, the receiving station will register the word "Ponis" in lieu of the word "Paris."

To avoid the action of the "parasites" on the receiving system, the apparatus may be 15 modified according to the invention in the following manner.

Each of the five emission contacts of the 20 telegraphic apparatus selected by way of example is divided into three parts. The transmission ring thus obtained is represented diagrammatically in developed form 25 in Fig. 3.

An elementary emission of the Baudot code such as "A" in Fig. 1 corresponds in 30 the modified system to the three contacts *a*, *b*, *c*. These contacts are utilized in the following manner.

In the first rotation of the distributor brushes (at the moment when the keys are 35 depressed) the emissions corresponding to the contact *a* will take place (Fig. 3). Then, after a predetermined time *T* selected so as to be greater than the mean duration of an uninterrupted series of atmospheric dis- 40 charges, the emissions *b* corresponding to the keys depressed at the first rotation will be produced automatically. The emissions *c* will likewise be produced after a further time *T*.

45 It may be provided, for example, that the emissions *b* will take place two seconds after the initial emissions *a* or after six consecutive rotations of the brushes if the latter rotate at 180 revolutions per minute. Likewise, the emissions *c* will take place two seconds after the emissions *b*, that is, four seconds after the initial emissions *a*.

50 Then the initial emissions *a* will initiate the operation of the series of three emissions, of which two, *b* and *c* are deferred, a series corresponding to the depressions of a key of the manipulator, or if preferred, to one of the 5 moments of the Baudot code.

An emission of the second set *b* or first 55 confirmation of the signal will have effect only in so far as it may have been preceded, according to the rule given, two seconds before, by the corresponding emission *a*.

Likewise, an emission of the third set *c*, 60 or second confirmation, will only act on the receiver if it has been preceded two seconds before by an emission *b* and four seconds before the initial emission *a*. Only the emission *c* acts on the receiver proper. The emissions *a* and *b* only prepare the arrival of 65

the active emission *c*. The preparatory emissions *a* and *b* act on preparing members controlled according to the period of time chosen *T* and brought to rest when the time *T* has expired. 70

It follows from the foregoing:

(1) That an isolated parasitic influence will have no effect on the Baudot receiver.

(2) That a series of parasitic influences will exercise action on the apparatus only 75 provided that such series responds in all respects to the rule enunciated above, and, in particular, provided that the successive discharges are in sufficient number and at intervals of exactly *T* seconds (2 seconds in 80 the example chosen). These conditions are very seldom realized.

The example chosen above—3 signals repeated at 2 seconds interval—may be modified according to requirements and depending on the numerical importance of the parasitic influences to be eliminated. It will often happen that one confirmation only will be necessary. Likewise, the time *T* between the signals may be increased or diminished 85 depending on circumstances and on the nature of the "parasites" to be eliminated. It should be noted that the duration of each emission may be as brief as possible. Thus, to take the first case where the duration of 90 each emission is 1/30th of a second and where the emissions of the same series are at intervals of 2 seconds, in sending a signal (a series of 3 emissions *a*, *b*, *c* of which two are deferred) the first emission will take 95 place at the time *t*, the second at the time *t' = t + 2* seconds, and the third at the time *t'' = t + 4* seconds or *t' + 2* seconds.

In order that a series of "parasites" may be eliminated it suffices that there should be 100 an absence of "parasites" during 1/30th of a second at one of the times *t*, *t'* or *t''*.

If the emissions are curtailed, it will be observed that the efficacy of the system is increased since the duration of conditional 110 absence of "parasites" at one of the times *t*, *t'* or *t''* is decreased.

If in the example given above each emission endured no more than 1/60th of a second, it would suffice that there be absence of 115 "parasites" during 1/60th of a second, instead of 1/30th, at one of the times *t*, *t'* or *t''* in order that, with the same efficacy, the manipulation may not be interfered with.

Fig. 4 represents the diagrammatic transmission of the word "Paris" according to the new method. Numerous "parasites" or foreign signals are indicated by hatched curves on the diagram. In spite of the multitude of these "parasites" it will be observed 120 that none of them answers the conditions imposed for the operation of the receiver and that, in consequence, no letter of the word "Paris" is distorted on arrival.

The method of this particular embodiment 130

ment of the invention may be adapted in various ways to all types of telegraphic apparatus working on the principle of synchronism.

- 6 By way of example, the transformation diagram of a Baudot telegraphic apparatus with 17 contacts devised in accordance with the invention is represented in Figs. 5 and 6—reception in Fig. 5 and emission in Fig. 6.
- 10 The developed rings E and F represent the normal receiving ring F with seventeen contacts associated with the continuous ring E. Four supplementary rings are placed on the distributor. One A of these comprises 45 contacts comprising 3 groups, namely, 1 to 15, 16 to 30 and 31 to 45. This ring is connected by the brushes b to a ring B which is connected electrically to the ring E by the conductor G shown in dotted lines.
- 15 A ring C comprising three groups of contacts (6a to 10a, 21a to 25a and 36a to 40a) is interconnected by the brushes c with the rings A and D. These contacts are connected electrically with the starting ends of 20 the windings of the corresponding electro-magnets. In the interest of simplicity such a connection between the contact I_{10} and the winding of the electro-magnet 10 is represented by a dotted line. The receiving 25 relay is shown at R. Its armature is connected electrically to the first sixteen contacts of the ring E. At the time of reception of a signal it bears on the contact α connected to the battery P_2 .
- 30 It is to be particularly noted that the brushes b and c rotate at one third the speed of the brushes a and that for the convenience of explanation E and F are taken to represent three successive developments of these 35 rings corresponding to three complete rotations of the brushes a. Each of the three series of contacts of the ring A is connected, as indicated, to a series of ten electro-magnets having double armatures and with self- 40 excitation.
- 45 The operation of an electro-magnet is as follows:
- The passage of a brief current in the winding, for example in that of 15, determines 50 the attraction of two armatures M_{15} , N_{15} ; one of them, the right hand one N_{15} , causes self-excitation, that is to say, the current of the local battery P traverses the resistance r and causes the adhesion of the two armatures M_{15} and N_{15} which then rest in contact with stop screws. Each of these electro-magnets remains excited until the starting end of its winding I_{15} is earthed by the brush c. Thus, the electro-magnet 15 receiving 55 a brief current by way of the contact 15 will adhere until the passage of the brush c over the contact 15, that is, after the brush a (the normal brush of the station) has performed three revolutions minus a 60 partial rotation corresponding to four con-

tacts of the distributor, the brushes c being four contacts in advance of the brushes b. An electro-magnet such as 10, the starting end I_{10} of which is not directly connected to the ring A, is brought back to rest by a 70 branch shown in dotted lines in the figure, leading to the corresponding contact 10a of the ring C which is earthed at the same time as the contact 10 of the ring A.

These electro-magnets, by means of their 75 second armatures M_{10} , M_6 , close the circuit on which depends the deferred following emission of the same series.

In these conditions the reception of the letter a will be effected, for example, in the 80 following manner.

On the first rotation of the brush a: reception of the initial emission by the contact 11 and the electro-magnet 11, adhesion of the 85 armatures N_{11} and M_6 .

At the fourth rotation: Reception of the second emission (first confirmation) by the contact 6 by way of the armature M_6 of the electro-magnet 11. The electro-magnet 11 will be brought back to rest by the earthing 90 of the starting end I_{11} of its winding by means of the brush c which will engage the contact 11 as soon as the brush b leaves the contact 6. These two brushes are angularly 95 displaced, as already mentioned, a distance equal to the spacing of four contacts.

At the seventh rotation: Reception of the third emission (second confirmation) or active emission by the contact 1. This emission is sent to the first of the indicators L of the 100 receiver, across the armature M_1 of the electro-magnet 6, which adheres until the brush b has left the contact 1 (as above).

The reception of the letter a is thus registered in accordance with the rule. If parasitic influences have manifested themselves during this time, certain ones of the thirty 105 electro-magnets shown in Fig. 5 have been able to function, but these parasitic influences have had no effect on the receiving indicators L. The rule of elimination predetermined in this example was that of triple 110 emission at intervals corresponding to three rotations minus five contacts.

To obtain in transmission automaticity of 115 the deferred emissions of the same series (emissions a, b, c, Fig. 3) there may be employed the same arrangement slightly modified.

Fig. 6 represents simply the modified portion. The contacts 11, 12, 13, 14 and 15 of the normal transmission set F are connected to the keys of the manipulator M. The contacts from 1 to 10 and 16 of the same set are permanently connected to the working battery P_1 . The contacts 16 and 17 are subject to correction. The operating relay R of the Hertzian emissions is connected between the rings E and B.

It follows that if no key of the manipula- 130

tor is depressed, there will be no emission save the emission for correction.

If the first key is depressed (letter *a*) there is obtained, at the first rotation, emission by the contact 11. The relay circuit is closed for example by the contact 11 of A and the electro-magnet 11 of which the armatures N_{11} and M_6 come in contact with their stop-screws. After a turning movement corresponding to three rotations minus five contacts, when the brush *b* will pass over the contact 6, the second emission will take place. In effect, the working battery circuit will be closed by the contact 6 of the ring F, the brush *a*, the ring E, the transmission relay, the ring B, the brush *b*, the contact 6 of the ring A, the armature M_6 of the electro-magnet 11, the winding of the electro-magnet 6 and earth. The transmission relay operates.

After a fresh turning movement corresponding to three rotations minus five contacts, the third emission will take place when the brush *b* will pass over the contact 1. This emission will take place this time across the indicator 1 which will give the control of the starting emission. The indicators are shown at L_1 , L_2 , L_3 , L_4 and L_5 .

The above adaptation embodied in an apparatus operating on the Baudot system of the mode of elimination of parasitic influences is given merely by way of example and of demonstration. It will be understood that without departure from the principle above indicated the same method may be applied to any other type or system of telegraphic apparatus depending on synchronism, such, for example, as the Murray apparatus, the Siemens, the multiplex Western Electric etc.

Further, it is easy, with a given apparatus, to contrive an arrangement which permits of instantaneous variation of the given rule for the elimination of interfering signals so as to obtain at any instant sufficient security for optimum efficacy of the installation.

The invention is further applicable to numerous systems of telegraphy in which perforated tapes are used for the transmission and reception of signals.

If in such systems disturbances of the signals transmitted by the sending station act on the receiving station, the receiving tape may present supplementary or erroneous perforations which do not correspond to the signals sent and the telegram may be unintelligible or difficult to decipher. This is the case, for example, if a multiplex telegraphic system be utilized, the receiver being connected by a relay to an ordinary telegraphic distributor, each sector of which is connected to an electric perforator.

If, in accordance with the present invention, several tape messages, for example three, have been obtained by repetition of

the signals emitted at the same speed, on superimposing the tapes there is obtained a resultant tape which presents only those perforations which correspond to the desired signals and those due to parasitic influences active during the sending of each telegram at the same relative instant. This last named condition is very difficult to fulfil if the number of repetitions is large.

It is not requisite that the speed of emission be the same for the several repetitions, which may, indeed, be effected by means of distinct pieces of apparatus. In this last mentioned case there may be effected at the receiving station local retransmission at the same speed of the several telegrams, which retransmission may be useful, for example, in the case where these telegrams are represented on tapes of different length and where it is desired to obtain tapes of the same length which can be superposed on one another.

This application of the invention to telegraphic apparatus for transmission and reception by means of perforated tapes will be better understood on reference to the following description where there is explained, by way of example, the application of the invention to a Baudot apparatus utilized for the transmission of messages by wireless.

Transmission.—The paper tape is perforated as usual in the system of telegraphy adopted and the tape message is transmitted successively by as many transmitters as there are repetitions wanted. Each of the transmitters is connected successively to the wireless transmitting apparatus by a distributor sector.

In this way the same letter will be repeated at constant intervals, corresponding on the tape to the number of letters which separate the keys of the transmitters.

The application of the method to the Baudot system is particularly simple; each transmitter being connected to one of the sectors of the distributor or plate of the sending station as is done usually.

The same perforated tape is engaged in the first, second, third transmitter etc., the lengths of tape by which these successive transmitters are separated corresponding to n_1 , n_2 . . . n_p letters. The number of letters between the several transmitters remaining constant throughout the transmission, the repetition of the signals is effected at constant time intervals t_1 , t_2 . . . which may be equal or unequal according as n_1 , n_2 . . . are equal or unequal.

To modify these time intervals, the speed of transmission remaining constant, it will suffice simply to modify the numbers n_1 , n_2 , n_p . It is understood that the intervals t_1 , t_2 . . . will vary if the speed of rotation of the distributor be varied, n_1 , n_2 remaining constant.

Reception.—The reception of the signals transmitted by the method just indicated is effected by means of a wireless receiving station connected by a relay to an ordinary telegraphic distributor, each sector of which is connected to an electric perforator. This perforator is constructed and connected in such wise that a perforation is made in the relative paper tape every time an electro-magnetic wave is received by the wireless receiving station.

In certain cases the perforator cannot be connected directly to the distributor; it must then be connected through the intermediary of a retransmitter, on account of the strength of current necessary to perforate the paper tape with sufficient rapidity.

The first transmission of a letter will be received by the first sector of the distributor and by the first perforator; that is to say, all the first transmissions are received on the same tape. In the same way the first repetition will be received on the second tape, the second repetition on the third tape and so on. If there are $P-1$ repetitions, there will be P tapes, each receiving one of the transmissions.

If "parasites" have been received by the wireless receiving station, perforations which do not correspond to any transmission are made in one or other of the tapes; but obviously there is infinitely small probability that perforations corresponding to distinct "parasites" will be found exactly at homologous points of these tapes.

On superposing these tapes so as to register the perforations corresponding to the same letter transmitted the composite tape obtained will present no perforation corresponding to "parasites".

On passing this composite tape into an ordinary automatic transmitter or one slightly modified for conjoint passage of P tapes, there will be brought into operation a translator connected to the transmitter, and the telegram received will be printed. If desired, and this will be the most frequent case, the correct telegram will be re-transmitted by means of an ordinary telegraphic transmission station, one of the sectors of which will be connected to the transmitter; at the same time the telegram will be printed to control the transmission.

Also, if desired, the telegram may be re-transmitted by wireless, the transmitter being connected to a distributor and the latter to a wireless station through the intermediary of a suitable relay.

Variant.—If preferred, tapes obtained at the receiving station may be passed into transmitters of which the transmission contacts are in series in such wise that only the perforations common to the P tapes occasion the passage of working current into the tele-

graphic retransmission or impression apparatus.

The use of this variant permits the rapid modification of the intervals of repetition.

In the adaptation which has just been described there may be utilized at the transmitting station and at the receiving station two sextuplex Baudot distributors; if there be adopted the system of three successive repetitions, three of the sectors of each of the distributors will serve for transmission and three of the sectors for reception. Instead of rotating the distributor at the normal speed of 180 revolutions per minute obviously it may be rotated much faster in order to obtain an increased output.

In the present invention the successive repetitions of a signal should be able to be checked independently of their nature and without the possibility of disturbances of foreign origin modifying the desired signals on reception. This should be understood in the most general fashion. The signal may, for example, be indicated by means of its coordinates x, y and z in space and time t ; one signal being received at x_0, y_0, z_0 , and at the time t_0 , the first repetition will be received at

$$x_1 = f_1(x_0, y_0, z_0, t_0) y_1 = \phi_1(x_0, y_0, z_0, t_0) z_1 = \psi_1(x_0, y_0, z_0, t_0)$$

and at the time $t_1 = \xi_1(x_0, y_0, z_0, t_0)$; f_1, ϕ_1, ψ_1 and ξ_1 being arbitrarily chosen functions of x_0, y_0, z_0, t_0 . Likewise the second repetition will be received at

$$x_2 = f_2(x_0, y_0, z_0, t_0) y_2 = \phi_2(x_0, y_0, z_0, t_0) z_2 = \psi_2(x_0, y_0, z_0, t_0)$$

and at the time $t_2 = \xi_2(x_0, y_0, z_0, t_0)$; f_2, ϕ_2, ψ_2 and ξ_2 being arbitrarily chosen functions of x_0, y_0, z_0, t_0 and so on for the repetitions following.

A signal being received at x_0, y_0, z_0, t_0 , to know if it is the signal desired, it will be necessary to observe if it is reproduced at x, y, z at the time t : then at x_2, y_2, z_2 at the time t_2 etc.

Other modes of checking a phenomenon will suggest themselves.

It will now be shown, in order that the scope of the present invention may be better appreciated, how the first adaptation given above by way of example may be readily generalized. In the following description the bracketed reference characters refer to analogous elements represented in the figures of the drawings.

At the sending station the distributor, Fig. 6, comprises n (3) series of q (5) contacts (F; 1, 2, 3, 4, 5; 1', 2', 3', 4', 5'; 1'', 2'', 3'', 4'', 5'') plus correction contacts (16, 17) if the number of repetitions desired is $n-1$ (2); this distributor is associated with an auxiliary apparatus such that the emissions by the contacts of the first series (F; 1, 2, 3, 4, 5) may be con-

trolled directly by the operator by known methods (Fig. 6; manipulator M , battery P_1); the $n-1$ (2) repetitions being produced automatically on the principle that a contact of order p (1') of the series s (2) occasions an emission only on the passage of the brushes a during their rotation of order X (4) for example, that if the contact d' of order p (1) of the series $s-1$ (1) has occasioned an emission on the passage of the brushes (a) during their rotation of order $X-n$ (1).

At the receiving end the distributor (Fig. 5; F ; E ; a) comprises the same number n (3) of series of q (5) contacts plus correcting contacts (16, 17) and is associated with an auxiliary apparatus such that a signal can only be perceived at the receiving station at its $n-1$ (2nd) repetition, the initial signal and its $n-2$ (1) first repetitions having for effect only to actuate the auxiliary apparatus and to prepare it to render the signal perceptible at the time of the $n-1$ th (2nd) repetition. With this object this auxiliary apparatus is so contrived that a signal can only act on it on the passage of the brushes (a) of the distributor on a contact of order p (1) of the series a (2) during the rotation of order X (4), for example, of the brushes (a) if it has been actuated by a signal on the passage of the brushes (a) on a contact of order p (1) of the series $s-1$ (1) during the rotation of the brushes (a) of order $X-n$ (1).

The auxiliary apparatus serving as a collector and selector may be of any one of many different types. It may consist, for example, of a second contact ring (A) associated with the first ring (F) of n (3) series of q (5) contacts plus correction contacts (16, 17); this second ring (A) comprises n (3) series of n (3) sub-series of q (5) contacts each; each series having besides a certain number (2) of correction contacts (46, 47; 48, 49; 50, 51), $n-1$ (2) being the number of repetitions desired. On this ring A rub brushes (b) which rotate at a speed

$$\text{equal to } \frac{1}{n} \left(\frac{1}{3} \right) \text{ of the speed}$$

of the principal brushes (a) ; each of these contacts is suitably connected to a distinct corresponding element capable of being modified (Fig. 5; contact 15 corresponds to the modifiable element N_{15} , M_{10} ; contact 10 corresponds to the modifiable element N_{10} , M_5 ; and contact 5 to the modifiable element L_5 , etc. . . .). These modifiable elements form n (3) series of n (3) sub-series of q (5) elements; each of the q (5) elements of the sub-series of order n (3) forms part of n (3) series simultaneously; if, for example, there be designated by P_{r^s} an element of order p of the sub-series of the

series s , the n elements p n^1 , p n^2 . . . p n^n are united in one only (L).

(In Fig. 5 the 3 series of contacts of the 2nd ring A are represented respectively by the numerals 1, 2, . . . 15, 46, 47; 16, 70 17 . . . 30, 48, 49; 31, 32 . . . 45, 50, 51; the 2nd sub-series of the second series by the contacts 21, 22, 23, 24, 25; the second sub-series of the second series of movable elements by N_{21} , M_{16} ; N_{22} , M_{17} , N_{23} , M_{18} ; 75 N_{24} , M_{19} ; N_{25} , M_{20}).

This description need not be enlarged on as it will be easy for those skilled in the art to complete it, being guided by the annexed drawings, Figs. 5 and 6, and by the text 80 corresponding thereto.

In the claims which follow there are also indicated in parentheses the elements of the annexed figures which are analogous to those which are designated by reference letters or by other reference characters such as letters or numerals.

By way of example there has been described more particularly the application of the invention to wireless telegraphy, but it 90 will be evident that the invention is applicable, as already stated, to signaling generally, this term being understood in the widest sense and comprising for example telemechanical transmission or transmission 95 by any means acting at a distance by wire or wireless.

Having thus fully described the invention, what we claim as new and desire to protect by Letters Patent is:

1. The improvement in the art of signaling devised to avoid the effect of disturbing influences, consisting in emitting signals, repeating the signals in accordance with a predetermined rule whereby the received 105 signals and repetitions of these signals are identified, and adopting only signals of which the initial receptions and their repetitions are correspondingly identified.

2. The improvement in the art of electric 110 telegraph signaling consisting in emitting a signal, utilizing the currents set up on emission of said signal to operate relay devices and thereby prepare circuits for transmission of a first repetition of the signal, repeating the signal, utilizing the currents set up on said repetition of the signal to operate relays and thereby prepare circuits for transmission of a second repetition, again repeating the signal, and resetting the re- 120 lays.

3. The improvement in the art of telegraph signaling consisting in emitting a signal, and repeating a plurality of times the signal emitted, storing the signal received and all its repetitions preceding the ultimate repetition, and causing the ultimate repetition to influence a receiver.

4. The improvement in the art of telegraph signaling consisting in emitting a sig-

nal, repeating the signal emitted, perforating a plurality of strips to form records of the signal and repetitions of the signal received, and superposing several strips to obtain a compound strip in which the intended perforations in the several strips are in register.

5. The improvement in the art of telegraph signaling consisting in emitting a signal, repeating the signal emitted, perforating a plurality of strips to form records of the signal and repetitions of the signal received, and re-transmitting the message denoted by corresponding perforations in all 10 the strips.

6. The improvement in the art of signaling, consisting in emitting a signal, repeating the signal emitted, perforating a plurality of paper strips forming records of 20 the signal and repetitions of the signal emitted, and preparing from said strips a record suitable for re-transmission of the signal.

7. A telegraph signaling system comprising circuit-forming connections, means for storing an initial signal and concomitantly therewith preparing circuits for reception of a confirmation of the signal, and means for storing said confirmation and concomitantly 30 therewith preparing circuits for reception of a subsequent confirmation of the signal, said first and second mentioned means being interlocked to permit reception of a confirmation only if preceded by an initial signal or 35 an earlier confirmation of the initial signal.

8. In a signaling system, in combination with circuit-forming connections, a distributor, rotary brushes co-operative with said distributor, said distributor comprising sectors of a number equal to the number of times each signal is to be transmitted, each sector including a plurality of contacts corresponding to the number of elements of the signaling code, an auxiliary distributor 40 comprising a set of contacts, rotary brushes co-operative with said auxiliary distributor, and storage devices co-operative with said auxiliary distributor.

9. In a telegraph signaling system, in

combination with circuit closing connections, a receiver, a transmitter including a main distributor comprising a number of sectors each including a number of contacts, the number of sectors corresponding to the number of times each signal is to be repeated 50 and the number of contacts of each sector corresponding to the number of elements of the telegraphic code, rotary brushes co-operative with said main distributor, an auxiliary distributor comprising contacts of 55 a number, a multiple of the number of contacts of the main distributor, brushes co-operative with the auxiliary distributor, rotatable at a speed a multiple of the speed of the first mentioned brushes, and storage 60 magnets connected to certain contacts of said auxiliary distributor, other contacts of said auxiliary distributor serving to ensure synchronization of said transmitter and said receiver.

10. In a wireless telegraph apparatus, in combination with the rings of a Baudot receiver, one ring being continuous and another ring having three sets of five segments and a pair of synchronizing segments, 75 brushes co-operative with the rings, three groups of self-holding magnets, a ring divided into three parts corresponding to the three groups of magnets, each part comprising segments connected to the relative magnets and to segments of the second ring, brushes connecting the three parts of said last mentioned ring to said continuous ring during three successive rotations, circuits 80 adapted to be prepared by energization of magnets affected by signals being transmitted, connections whereby the magnets are reset after preparation of the respective circuits, a set of punches, and connections whereby each punch is operated at the third 85 transmission of a signal.

In witness whereof, I have hereunto set my hand this 15th day of May, 1925.

CHARLES VERDAN.

In witness whereof, I have hereunto set my hand this 15th day of May, 1925.

LOUIS MARIE JEAN LOISEAU.
